UNITED STATES PATENT OFFICE.

JOHN MALKEVIC, OF AMSTERDAM, NEW YORK.

PICTURE-FRAME.

1,296,544.

Specification of Letters Patent.

Patented Mar. 4, 1919.

Application filed July 19, 1918. Serial No. 245,625.

To all whom it may concern:

Be it known that I, JOHN MALKEVIC, a citizen of Russia, residing at Amsterdam, county of Montgomery, and State of New York, have invented certain new and useful Improvements in Picture-Frames, of which the following is a specification.

This invention relates to improvements in picture frames, and has as its special object the provision of a novel and attractive type of frame which may be reversed, both sides being alike.

A further object is to provide means combined with the frame whereby the glass or transparent picture is secured in position within the frame in a safe and effective manner.

These and other like objects are attained by the novel construction and combination of parts hereinafter described and shown in the accompanying drawing, forming a material part of this disclosure, and in which:—

Figure 1 is a front view showing a picture frame made in accordance with the invention.

Fig. 2 is a top view of the same.

Fig. 3 is a transverse sectional view taken on line 3—3 of Fig. 1.

Fig. 4 is a side elevational view of the same.

Fig. 5 is a fragmental perspective view showing one of the corners of the same.

Fig. 6 is a perspective view showing a detail of construction, and

Fig. 7 is a like perspective detail view, showing another element used therein.

The frame is comprised of a plurality of longitudinally disposed bars interengaged with cross bars, which in turn are connected by transverse bars, and with each other, the several bars having similarly shaped faces by which they are engaged.

The side elements are composed of bars respectively 10, 11, 12 and 13, arranged in pairs, the faces of the bars containing transverse recesses 15, receptive of the cross bars 16, 17, 18 and 19, also arranged in pairs and received within the recesses 15. These cross bars are also provided with recesses 15 of a similar nature and engageable therein, are

the shorter connecting elements 20, having similarly recessed faces 21, the outer ends or abutments of the walls extending over the plain backs of the longitudinal bars 10 and 13, while the inner walls of the recesses contact with the backs of the longitudinal bars 11 and 12 so as to bind them firmly in an adjusted position.

Certain of the connecting elements 25, as shown in Figs. 2 and 3, are engaged with the cross bars 16 and 18, there being a space between their inner adjacent edges receptive of the glass plate 30, the same resting upon the lower connecting element at the bottom of the frame, and also against the back of the connecting element used at the sides of the frame, so that when the frame is held in a substantially vertical position, the glass is maintained firmly therein and prevented from dropping through or moving laterally, thus providing a tight means for the glass.

The foregoing description, taken in connection with the drawing, is believed to present a disclosure enabling one versed in art to make and use a frame in accordance with the invention.

Having thus described my invention what I claim as new and desire to secure by Letters Patent, is.

1. In a picture frame or the like, the combination with a plurality of longitudinally disposed pairwise arranged members having transverse recesses, forming the sides thereof, recessed cross members inter-engaged with said longitudinal members forming the ends, a plurality of recessed connecting elements engaged within the recesses of said longitudinal and cross members respectively, outer abutments of the walls of the recesses of said connecting elements extending over the plain backs of one pair of said longitudinal members, and the inner walls of said recesses contact with the backs of the other pair of said longitudinal members, and means formed through said connecting members at one end of said frame, receptive of a plate.

2. In a picture frame, the combination with a plurality of longitudinally disposed pairwise arranged bars having transverse

recesses, a similar plurality of recessed transverse bars arranged at the end of said longitudinal bar, recessed connecting elements engageable with said transverse and longitudinal bars respectively, the connecting elements at the upper portion of said frame being placed so as to permit the insertion of a

plate, and means formed with the backs of said connecting elements adapted to hold said plate against lateral or longitudinal movement.

In testimony whereof I have affixed my signature.

JOHN MALKEVIC.
